BALL POINT PEN

Robert H. Ensign, Bronxville, N. Y., and Danforth Car-
dozo, Jr., Weston, Conn., assignors to Scripto, Inc., a
corporation of Georgia

Application June 23, 1955, Serial No. 36,644

Term of patent 14 years

(Cl. D74—20)

Fig. 1

Fig. 2

Fig. 3

Fig. 4

Fig. 1 is a front elevational view of a ball point pen showing our new design;

Fig. 2 is a side elevational view of the ball point pen shown in Fig. 1;

Fig. 3 is a top plan view thereof; and

Fig. 4 is a cross sectional view thereof taken substantially on lines 4—4 in Fig. 1.

We claim:

The ornamental design for a ball point pen, as shown.
